CLAIM

The ornamental design for an inverter, as shown and described.

DESCRIPTION

FIG. 1 is a front elevational of an inverter showing my new design;

FIG. 2 is a rear elevational view thereof;

FIG. 3 is a top plan view thereof;

FIG. 4 is a bottom plan view thereof;

FIG. 5 is a left side view thereof;

FIG. 6 is a right side view thereof;

FIG. 7 is a top perspective view thereof;

FIG. 8 is a bottom perspective view thereof; and,

FIG. 9 is a perspective view of the inverter with the lid open. The broken lines in the drawings illustrate portions of the inverter which form no part of the claimed design.
